UNITED STATES PATENT OFFICE.

ROY A. RIDDLE, OF NEW ORLEANS, LOUISIANA.

PAPER WEIGHT.

Application filed October 4, 1926. Serial No. 139,450.

The present invention relates to improvements in paper weights, and has for an object to provide an improved paper weight in which papers may be placed under the weight without requiring the lifting of such weight.

Another object of the invention resides in providing a novel form of stationery device or desk fixture in which papers may be anchored by the use of one hand only.

A further object of the invention is to provide a simple and inexpensive paper weight in which the moving part will be automatic and reliable in action.

With the foregoing and other objects in view, the invention will be more fully described hereinafter, and will be more particularly pointed out in the claim appended hereto.

In the drawings, wherein like symbols refer to like or corresponding parts throughout the several views,

Figure 1 is a top plan view of an improved paper weight constructed according to the present invention.

Figure 2 is a side elevation thereof with the weight member in the lower position, and

Figure 3 is a similar view showing the weight in partially elevated position above a stack of papers.

Referring more particularly to the drawings, 4 designates a block preferably of heavy material from which extends the arm 5 carrying the cage for the ball weight 6. The cage is affixed to the under portion of the arm in any appropriate manner and comprises two yoke pieces set at substantially right angles with their intermediate portions crossed beneath the free end of the arm 5 and secured at their crossed portions. The four arms of the yoke extend down at substantially 90 degrees apart and confine the ball 6 on the four sides. The arms are made with the diagonal portions 7 and the vertical portions 8 extending downwardly therefrom and having their lower free ends inturned, as indicated at 9 forming lugs for arresting the downward movement of the ball 6 and its escape from the cage. If desired the arms may be of metal or some bendable material in order to admit of their being pushed out-

wardly to receive, and permit of the removal, of the ball 6.

In the use of the device, the arms are considerably longer than the diameter of the ball 6, so that the ball is floatingly held within the cage. The arrangement is such that the lower part of the ball 6 will rest by its weight upon the surface of the desk or other supporting surface when the block 4 is placed upon such desk, but when the device is lifted up from the desk the ball 6 will descend against the lugs 9 and these lugs will hold the ball while being lifted and carried about from place to place. The spherical surface of the ball permits of the pushing of the papers indicated at 10 in Figure 3, beneath such ball, such spherical surface guiding the papers down toward the desk which usually has a polished finish to enable the papers to be slid easily under the weight. The ball rests upon the supporting surface at a theoretical point which further facilitates the receiving and removal of papers. The ball will preferably be of some heavy metal which will adequately hold the stack of papers 10 when inserted therebeneath. As many papers may be slipped under the ball as desired, the ball having ample play upwardly in the cage. The device permits of the placing of papers under the weight with only one hand and without the hands touching the paper weight.

It is obvious that various changes and modifications may be made in the details of construction and design of the above specifically described embodiment of this invention without departing from the spirit thereof, such changes and modifications being restricted only by the scope of the following claims:

What is claimed is:—

A movable paper weight arrangement, comprising a solid block, an arm projecting from said block, a downwardly projecting cage attached to said arm near the outer end thereof and provided with engaging claws, and a ball mounted in said cage and normally rotatably held therein by said claws but adapted to project beneath said claws when the said block is supported on a flat surface.

ROY A. RIDDLE.
